United States Patent Office

Des. 207,565
Patented May 2, 1967

207,565 DISPLAY RACK

Shepard H. Whitman, Chicago, Ill., assignor to Master
Bronze Powder Company, Inc., a corporation of
Indiana

Filed Oct. 21, 1966, Ser. No. 4,365

Term of patent 14 years

(Cl. D80—9)

Fig. 3.

Fig. 4.

FIG. 1 is a front perspective view of a display rack embodying my new design;

FIG. 2 is an elevational view taken from one end thereof, with portions broken away for convenience of illustration;

FIGURE 3 is a top plan view thereof; and

FIGURE 4 is a rear elevation thereof.

The dominant features of my invention are shown in solid lines it being understood that the broken line representation of merchandise on the shelves in FIG. 1 is for purposes of illustration only.

I claim:

The ornamental design for a display rack, as shown.
